UNITED STATES PATENT OFFICE.

FRANK H. ILSE, OF CHICAGO, ILLINOIS.

CURTAIN FOR VEHICLES.

1,018,498.

Specification of Letters Patent.

Patented Feb. 27, 1912.

Application filed June 17, 1911. Serial No. 633,781.

To all whom it may concern:

Be it known that I, FRANK H. ILSE, a citizen of the United States, residing at Chicago, in the county of Cook and State of Illinois, have invented certain new and useful Improvements in Curtains for Vehicles, of which the following is a specification.

This invention relates to curtains designed to be used in combination with the ordinary foldable top of automobiles and other vehicles employing such tops; and among the leading objects of the invention are: 1st, to provide curtains and supporting and attaching means therefor of such a character that 10 the curtains may be quickly and easily applied wholly from the inside of the car; 2nd, to provide curtains and supporting and attaching means therefor of such a character as to permit the folding of the top without disconnecting the curtains from their immediate supporting devices or disconnecting the latter from the top itself; 3rd, to provide a construction permitting the folding and storage of the curtains, when not in 20 use, in such a manner as not to injure the curtains and not to obstruct any otherwise usable space within the body of the vehicle; 4th, to provide curtains and supporting and attaching means therefor of such a character 30 as to secure, in combination with the top and fixed parts of the body, a practically completely inclosed or limousine body.

To these ends my invention consists in the novel structural features for effecting the 35 above recited objects hereinafter described and particularly pointed out in the claims.

In the drawings, Figure 1 is a side elevational view of my improved curtains attached to one side of a vehicle provided 40 with a vehicle top frame. Fig. 2 is a vertical longitudinal sectional view of Fig. 1. Fig. 3 is a detached sectional view showing the curtains in folded position against one of the ribs of the top frame. Fig. 4 is a detached sectional view of one of the ribs designed to show the protector at the upper 45 ends of the curtains. Fig. 5 is an edge view of Fig. 6. Fig. 6 is a detailed view of one of the side curtains, parts being broken away. Referring to the drawings, the vehicle 50 body 7 is of the ordinary type used on automobiles and carriages and is provided with a top covering consisting of the bow ribs 8 and 9 which are pivoted, at their lower ends, 55 to the supports 10 secured to the vehicle

body and to which ribs 8 and 9 angularly disposed ribs 11 and 12 are respectively pivoted. A top covering 13 is secured to the ribs and to the rear end of the body of the vehicle. The top frame and covering are 60 of the ordinary construction and constitute no part of the invention herein, except in so far as the framework is used in combination with my invention.

In the drawings the top covering is shown 65 in its open or operative position extending from the rear of the body forwardly to the wind-shield 14. When it is desired to fold, the pivotal connection between the ends of the rib 8 and the support 10 is disconnected, 70 whereupon the angular rib 12 folds against the back of the body of the vehicle and the remaining ribs may be folded upon the rib 12 in successive order by shifting the rib 8 rearwardly until it lies against the rib 9, 75 which rib 9 in turn lies against the rib 12 and the rib 11 will lie against the rib 8. Between the ribs 11 and 12, extending longitudinally of the body of the vehicle and upon opposite sides thereof, I secure curtain supports 15 and 16, which are flexible 80 so as to fold with the top, and in the preferred form, consist of wire cables, that may be tightened or loosened by means of turn buckles 17. Upon these supports one or 85 more side curtains are slidably mounted, there being preferably three curtains upon each side of the vehicle, the curtains 18 extending between the rib 9 and the rear end 19 of the top 13; the curtain 20 extending 90 between the rib 8 and the rib 9 and the curtain 21 extending between the wind-shield 14 and the rib 8.

As the constructions of all of the side curtains herein shown are substantially 95 identical, except as to their shape, I will, therefore, only describe one curtain, which description will serve for all.

Each curtain consists of a plurality of sections, such as 22, 22^a, 22^b, etc., (Fig. 6,) 100 of flexible, water-proof material, each section being provided with a window of celluloid or any other suitable transparent material. In my preferred construction I connect adjacent sections by hinge-joints each 105 formed by a stitched transverse loop or pocket 26 within which is inserted a filler-rod 24 of ratan, metal, or other suitable material that acts as a stiffener, and facilitates the ready-folding of the sections of 110

the curtain upon each other, after the fash-
ion of an accordion-plait. Apertures 27 are
provided at the top edge of each section and
through which apertures the side supports
5 15 and 16 extend.

When the sections composing each curtain
are strung upon the supports, it will be
readily seen that when the curtain is in an
operative position, as when it is in use, the
10 several sections will all be substantially in
the same plane, but when it is desired to
place a curtain in an inoperative position,
the sections may be folded one upon the
15 other by sliding the same along their sup-
port and in such folded position they can
be then swung upwardly and secured be-
neath and adjacent the top covering, as
shown in Fig. 3, wherein the curtain 20 and
20 the oppositely disposed curtain 20^a are fold-
ed against the rib 9 and held by the retain-
ing means or straps 25. The curtain 21 and
the opposite curtain thereto may both be
folded in the same manner against the rib
8, which is equally true of the curtain 18
25 and the opposite curtain thereto, which may
be folded against the rib 12 and held by
means of straps, or any other suitable re-
taining means desired.

At suitable points both on the frame top
30 and on the body of the vehicle latches 28 are
placed which may be of any desired con-
struction and which coöperate with suitable
openings formed in the curtains themselves,
or in tabs 29 secured to the curtains to hold
35 said curtains at their lower ends, such fas-
tening devices being operable wholly from
within the body of the vehicle. In my pre-
ferred construction I also attach tabs 30
40 to one or more of the curtains, which are
also provided with suitable latch openings,
whereby if it is not desired to have the cur-
tain entirely inclosing the vehicle body, a
slight opening may be obtained by securing
the tabs 30 to one of the latches and thereby
45 partially or entirely folding one of the
sections of the curtain upon an adjacent
section.

In order that no rain, dust or other sub-
50 stances may enter the inclosure formed by
the curtains when in an operative position,
I secure protectors 31 to the top 13 and on
opposite sides above the upper ends of the
curtains, which protectors extend below the
55 supports 15 and 16, thereby forming a suf-
ficiently tight joint to keep out rain, dust
or other substances.

It will be readily seen from the forego-
ing description that if the curtains are in
60 an inoperative position and it is desired to
immediately use the same, any one or all
can be readily detached and brought into
operative position and there securely held,
this being done wholly from within the
65 body of the vehicle. It will also be ap-
parent that when the sections of each cur-

tain are folded, a compact body is formed
which may be easily thrown into inopera-
tive position without in any way bending
and thereby injuring or breaking the trans-
parent material constituting the windows,
70 and that all of the side curtains when in
an inoperative position together with their
supporting cables may be readily folded
with the top frame when it is desired to
throw the entire frame construction into a
75 folded position.

Having therefore described my invention,
I claim:

1. In combination with a frame and cover-
ing of a foldable vehicle top, flexible curtain
supports extending longitudinally of the top
80 on either side of the latter, respectively,
foldable curtains slidably mounted on said
supports, and means on the under side of
the top covering for securing the folded cur-
85 tains against the latter.

2. In combination with a frame and cov-
ering of a foldable vehicle top, flexible cur-
tain supports extending longitudinally of
the top on either side of the latter, respec-
90 tively, and foldable therewith, foldable cur-
tains slidably mounted on said supports,
means on the under side of the top covering
for securing the folded curtains against the
95 latter, and means operable from within the
body of the vehicle for attaching the free
margins of said curtains to the top frame
and body of the vehicle.

3. In combination with the frame and
covering of a foldable vehicle top, cables
100 extending longitudinally of the top on
either side between the front and rear ends
thereof, and curtains each comprising a plu-
rality of sections foldably connected by
vertical hinge joints, said sections being
105 provided adjacent to their upper ends with
eyes slidably engaging said cables.

4. In combination with the frame and
covering of a vehicle top, cables extending
110 longitudinally of the top on either side
between the front and rear ends thereof, and
curtains each comprising a plurality of sec-
tions of flexible material foldably connect-
ed by vertical hinge joints and provided
115 with windows therein, said sections being
provided adjacent to their upper ends with
eyes slidably engaging said cables.

5. In combination with the frame and
covering of a foldable vehicle top, cables
extending longitudinally of the top on
120 either side between the front and rear ends
thereof, and curtains each comprising a plu-
rality of sections of flexible material fold-
ably connected by vertical hinge joints, each
of said joints being formed by a stitched
125 loop or pocket formed in the material of the
curtain and a stiffener inserted in said loop
or pocket, said sections being provided ad-
jacent to their upper ends with eyes slid-
ably engaging said cables.

6. In combination with a frame and covering of a foldable vehicle top, flexible curtain supports extending longitudinally of the top on either side of the latter, respectively, and foldable therewith, and curtains slidably mounted on said supports, each of said curtains comprising a plurality of sections of flexible material foldably connected by vertical hinge joints and provided with windows therein.
- 5 FRANK H. ILSE.
